Application July 5, 1946, Serial No. 131,330

Term of patent 7 years

(Cl. D81—10)

To all whom it may concern:

Be it known that I, Wayne A. Gustafson, a citizen of the United States, residing at Minneapolis, in the county of Hennepin and State of Minnesota, have invented a new, original, and ornamental Design for Portable Electric Space Heater, of which the following is a specification, reference being had to the accompanying drawing, forming part thereof.

Figs. 1 and 2 of the drawings are perspective views taken from the forward and rearward quarters, respectively, of a portable electric space heater, showing my new design.

I claim:

The ornamental design for a portable electric space heater, as shown.

WAYNE A. GUSTAFSON.
